UNITED STATES PATENT OFFICE.

WILLIAM G. MUELLER, OF CHICAGO, ILLINOIS, ASSIGNOR, BY MESNE ASSIGNMENTS,
TO ALEC J. GERRARD, OF CICERO, ILLINOIS.

BOX-STRAPPING MACHINE.

Application filed December 31, 1920. Serial No. 434,810.

To all whom it may concern:

Be it known that I, WILLIAM G. MUELLER, a citizen of the United States, residing at Chicago, in the county of Cook and State of Illinois, have invented certain new and useful Improvements in Box-Strapping Machines, of which the following is a specification.

The present invention relates to baling devices and is particularly concerned with an efficient wire-tying machine for binding boxes and the like with round wire.

The general purposes of this invention are to provide a machine of the kind specified which is portable; which is of light and compact construction; which may be either hand or motor-operated; and which may be handled by the operator, in transporting it about or positioning it upon a box to be wired, with such facility as to adapt the machine most advantageously for use in shipping rooms and like places where employment of the ordinary, stationary wire-tying devices is often-times prohibitive, due to the number and varied sizes of the boxes to be wired and to the congestion of the room. The machine of this invention may be used with ease to wire boxes of any size, since, to use this machine, it is only necessary that the same be placed upon a substantially flat surface of the box and positioned contiguous with the plane of the proposed loop of wire to be placed therearound.

Another equally important object of the invention is the provision of a machine having adjustable means to tension the wire to a degree of tautness which may be regulated according to the strength of the wire and the construction of the box to be strapped; means to intertwist the overlapped ends of the wire; and means to cut off the remaining excess wire at points closely adjacent the ends of the twisted portions.

Still another object is the provision of a machine wherein the tensioning, the twisting and the cutting operations occur automatically and in properly timed sequence.

With these and other objects in view, the invention resides primarily in the provision of novel and adjustable tensioning means,

of means for throwing the twisting mechanism into operation when the wire is drawn to the desired tightness, and out of operation after the completion of the desired number of twists and cutting off the excess ends, and of means by which the synchronization of the machine operation is effected.

Numerous other objects and advantages of the invention will appear as the nature of the same is better understood from the accompanying drawings and the following detailed description based thereon.

One embodiment of the invention is here illustrated and described for the purpose of exemplification, but, inasmuch as the invention is readily capable of modification in unessential details of construction and arrangement of parts, it should be understood that the drawings and description are not intended to limit unnecessarily the spirit of this invention or the scope of the appended claims.

In the drawings:

Fig. 1 is a view in side elevation, showing the machine positioned upon a box and engaging the ends of a tying wire, the parts being in their respective positions prior to the tensioning, twisting and cutting operations;

Fig. 2 is a top plan view, with the cover removed, and a portion of the mechanism and machine casing broken away at the left of the view to disclose the mechanism therebelow;

Fig. 3 is a vertical longitudinal section through the machine, taken on the line 3—3 of Fig. 2;

Fig. 4 is a vertical transverse section, taken on the line 4—4 of Fig. 2, and illustrates a portion of the tensioning mechanism;

Fig. 5 is a similar section, taken on the line 5—5 of Fig. 2, and illustrates the twisting mechanism;

Figs. 6 and 7 are similar views, taken on the lines 6—6 and 7—7, respectively, of Fig. 2, and illustrate the mechanism for unclutching the twisting mechanism;

Figs. 8 and 9 are vertical views illustrating the cutting mechanism, Fig. 8 being a

transverse section on the line 8—8 of Fig. 2, and Fig. 9 being an end elevation of the machine with certain movable parts removed for clearness; and

5 Fig. 10 is a fragmentary top plan view of the end portions of the tying wire when the twisting operation has been completed.

Referring now in detail to the drawings, and particularly to Figs. 1, 2 and 3 thereof, 10 the numeral 10 designates in general the casing of the machine, within and upon which is mounted the various mechanisms constituting the invention. A cover 11 effectively closes the top of the casing 10, being secured thereto by screws or other suitable means. 15 This cover is provided with a rigid handle 12 of inverted U-shaped form, which is positioned centrally of the same and serves as a convenient means for transporting or positioning the machine.

In order to illustrate clearly the general manner in which this machine is used, Fig. 1 shows the same placed upon a box 13. A wire 14, passed around the periphery of the 20 box, has its ends attached, at the proper points, to the mechanism of the machine. Upon operation of the machine, the wire 14, when thus attached, will be tensioned, the overlapped ends twisted together and the excess ends thereof subsequently cut off.

A power transmitting shaft 15 is rotatably mounted in casing 10 lengthwise thereof. One end of this shaft is journaled in a longitudinally adjustable screw plug bearing 16 25 threaded into an end wall of the casing, and the other end is journaled in an elongated sleeve 17 formed integral with a transverse partition 18 of the casing and disposed adjacent the opposite end wall thereof.

40 A collar 19 is fixedly secured to shaft 15 by means of a pin 20 or the like. One side of this collar bears against the adjacent end of the bearing sleeve 17, and the other side of the collar is provided with longitudinally 45 projecting ratchet teeth 21. A sleeve 22 is loosely mounted on the shaft 15, and has its outer surface spirally threaded to constitute a worm. One end of this sleeve or worm is provided with ratchet teeth 23 which are 50 complementary to, and normally intermesh with, the ratchet teeth 21 of the collar 19. The other end of the sleeve 22 abuts against a relatively large disk 24 also mounted loosely on the shaft 15. A strong spiral spring 55 encircles the shaft 15 and is confined thereon between the disk 24 and a smaller washer 26. This washer in turn abuts against a small gear wheel 27, which is keyed to the shaft 15 in such a way as to prevent relative rotation therebetween while permitting longitudinal movement of the former along the latter. A ball bearing raceway 28 is secured to that side of the gear wheel 27 opposite the washer 26, and receives a plurality of ball 60 bearings 29, which are retained thereagainst

by a similar oppositely disposed but normally stationary raceway 30 carried by the previously mentioned screw plug bearing 16.

A stub driving shaft 31 is journaled in an end wall of the casing 10, above and parallel to the shaft 15, and is provided, within the casing, with a small fixed pinion 32 having relatively wide teeth which intermesh with the teeth of the gear wheel 27 on the shaft 15. A hand wheel 33, which is rotated by means of a handle 34 attached thereto, is keyed to the end of the shaft 31 exteriorly of the machine casing.

From the construction thus far described, it will be understood that shaft 15 will be 60 rotated in the direction opposite that of the hand wheel 33, and that the gear wheel 27 will always intermesh with the pinion 32 regardless of the position which said gear wheel assumes on its shaft due to manipulation of the screw plug 16 in varying the compression exerted against disk 24 by the spring 25. It will also be understood that the function of this spring is to clutch the worm 22 to the collar 19 by serving to hold in intermeshed relation the ratchet teeth of these elements.

As shown in Figs. 3 and 4, a wire-tensioning shaft 35 is journaled in the side walls of the casing below and at right angles to shaft 15, and has keyed thereto a worm gear 36 which intermeshes with the worm 22 on shaft 15. One end of the shaft 35 extends exteriorly of the machine casing and is there provided with a drum 37. This drum is 100 keyed to its shaft and has two pair of intersecting parallel kerfs 38 cut in its outer side to provide convenient means for engaging one end of the wire, as shown in Fig. 1.

It will be appreciated from the preceding 105 description of the wire-tensioning shaft and its associated parts and drive that when the handwheel 33 is turned in a clockwise direction, as viewed from the right in Figs. 1, 2 and 3, the drum 37 will be rotated slowly 110 in a counter-clockwise direction and will proceed to tension the wire 14 attached thereto. When this increasing tension becomes greater than the adjustable force exerted by the spring 25 on the worm 22, the wire-tensioning drum 37, shaft 35 and work gear 36 will come to rest and the continued rotation of the worm 22 will cause the same to unscrew itself along the now stationary threads of the worm gear 36, thus disengaging the 115 clutch teeth 21 and 23. The tensioning mechanism thus remains stationary, the angle of the worm teeth being such as to prevent its being rotated back into engagement with the clutch by the pressure applied longitudinally 120 by the spring 25. When the tension on the wire is released because of the subsequent cutting of the same the worm 22 will of course become clutched again to the collar 125 19.

A shaft 39 is rotatably mounted in axial alignment with, and in end-to-end relation to, the power transmitting shaft 15, one end of the shaft 39 being journaled in the bearing sleeve 17 of the casing partition, and the other end being journaled in a housing 40 which is formed in the end wall of the casing and projects exteriorly therefrom. The contiguous ends of the shafts 39 and 15 are provided with complementary ratchet teeth 41 which intermesh when the two shafts are brought together, and function to constitute a clutch therebetween. The outer end of the housing 40 is closed by a plug 42 spaced a sufficient distance from the end of the shaft 39 to permit a longitudinal shifting of said shaft in order to clutch or unclutch the same with the shaft 15. Cavities 43 are bored in the opposing faces of the plug and shaft to receive and seat a spring 44 therebetween. This spring functions to shift the shaft 39 longitudinally into intermeshed or clutched engagement with the shaft 15.

Intermediate the ends of the shaft 39, an annular groove 45 is formed therein and serves to receive, when the shaft is shifted to the left as viewed in Fig. 3, the nose of a plunger 46. This plunger is seated in a recess of the casing, as shown in Fig. 6, and is pressed into the groove 45 of the shaft by means of a small spiral spring 47 positioned also in the recess.

The purpose of this plunger is to hold the shaft 39 in unclutched relation to the shaft 15, and, in order to withdraw the plunger and to clutch the shafts, a finger 48 is formed on the shank of the plunger and extends upwardly at right angles thereto. The means for operating this finger consists of a flat narrow slide 49 which is positioned longitudinally of the machine casing and is supported in guideways 50 formed in the casing and partition. The finger 48 projects into one of these guideways. This slide is best illustrated in Fig. 2. That portion of the slide adjacent the finger has cut therein a tapered notch 51. An abrupt notch 52 is cut in the opposite side of the slide 49 near its other end, and receives a portion of the previously described disk 24 on the shaft 15.

It will be evident from the foregoing description that when the tension of the wire 14 has reached the predetermined amount, the disk 24, in shifting to the right with the worm 22, will carry the slide 49 with it, thus causing the finger 48 to cam against the edge of the notch 51 and be forced inwardly, whereupon the nose of the plunger 46 is withdrawn from its groove and the shaft 39 allowed to clutch with the shaft 15. Furthermore, when the disk 24 returns to its normal position, the slide 49 will cease to bear inwardly against the finger 48 and

the nose of the plunger will again be pressed against the shaft 39. Each of the views of the drawings, with the exception of Figs. 6 and 7, illustrates the shaft 39 clutched to the shaft 15. This clutching only occurs, however, when the wire 14 is under the proper tension and the twisting mechanism is in operation.

Referring particularly to Fig. 5, a small coaxial pinion 53, provided with relatively wide teeth, is formed on the shaft 39 between the groove 45 and ratchet clutching teeth 41 thereof. This pinion intermeshes with and drives a gear wheel 54 keyed to a short counter-shaft 55, which is journaled in the casing 10 below and to one side of shaft 39, in parallel relation thereto. A pinion 56 is also keyed to the counter-shaft 55, and intermeshes with and drives a gear wheel 57. This gear wheel is keyed to a relatively long shaft 58 at a medial point thereon, said shaft being journaled in the end wall of the casing and in the partition 18 at a point below and to one side of the shaft 39, in parallel relation thereto. The gear wheel 57 has provided near its periphery, on the side thereof opposite the partition 18, a projecting lug 59, the purpose of which will be set forth later.

A small wire-twisting pinion 60 occupies, together with the lower portion of the gear wheel 57, a transverse slot 61 in the base of the machine casing, and is intermeshed with and driven by said gear wheel. The pinion 60 is formed integral with a stub shaft 62 which is journaled at both ends in the side walls of the slot 61. A deep radial slot 63, which is slightly greater in width than the diameter of the wire 14 to be twisted, is cut both in the pinion 60 and its stub shaft, lengthwise thereof. The side walls of the slot 61 in the casing have formed therein, in substantial alignment with the slot 63 of pinion 60 when the same is in a horizontal position, deep circular edged kerfs 64, to permit the two overlapped ends of the wire 14 to be received in the slot of the wire-twisting pinion 60. The above mentioned side-walls of the slot 61 taper downwardly and outwardly as at 65, from the lower outer edge of the kerfs 64, thus permitting the machine to be easily withdrawn from under the wire 14, after said wire is tied, by lowering the intertwined wire portions gradually to the surface of the box 13. It will now be understood that when the shaft 39 is driven by being shifted into clutching engagement with shaft 15, the wire-twisting pinion 60 will be rotated in a clockwise direction as viewed in Fig. 5, assuming, of course, that the hand-wheel 33 is turned, as is customary, in a clockwise direction.

The relative sizes of the pinion 60 and gear wheel 57 are determined with the end in view that the former make three complete

revolutions to one revolution of the latter, as in twisting the wire it is desirable that the same be given three, and only three twists. The previously mentioned lug 59 is therefore provided to actuate certain mechanisms for shifting the shaft 39 out of clutching engagement with the shaft 15, when the gear wheel 57 has completed one revolution.

The means for shifting the shaft 39 out of clutching engagement with shaft 15 after said clutching engagement has been brought about by the spring 44 upon the withdrawal of the nose of the plunger 46 from the groove 45, is as follows: That portion of the base 15 of the casing 10 between the gear wheel 57 and the end wall of the casing, extends up to within a short distance of the underside of shaft 39. The upper surface of this solid portion supports an angularly shaped plate 66 which is pivoted at one corner on an upright pivoting pin 67. This construction is illustrated in Figs. 2, 3, 6 and 7. An edge 68 of the plate 66 adjacent the pivoting pin 67 is so cut that it will normally lie at an angle to the longitudinal axis of the casing 10, for a purpose later stated. An arm 69 is positioned upon the plate 66, and has one of its ends pivoted on the pivoting pin 67. The free end of this arm carries a vertical 30 pin 70 which projects both above and below the arm. The upper projection thus formed engages at all times in the groove 45 of the shaft 39, while the lower projection is received in a short arcuate slot in the plate 66.

35 A horizontal transverse guideway is formed in the solid portion of the casing below the plate 66 and adjacent the gear wheel 57. A slide 71 reciprocates within this guideway and is normally held at the end of the 40 same which is adjacent the pivoting pin 67, by the action of a spiral spring 72 positioned also in the guideway. A lug 73 projects upwardly from the slide 71 and bears against the edge 68 of the plate 66. When 45 the slide 71 is shifted away from its normal position and against the spring 72, the lug 73 will cam against the edge 68 of the plate 66, and in the consequent swinging of the plate 66 about its pivot point, the pin 70 of 50 the arm 69, being in that edge of the arcuate slot nearest the slide 71, will be shifted likewise about the pivoting pin of its arm, and will in turn shift the shaft 39 out of clutching engagement with the shaft 15.

Because of the aperture in plate 66 being in the form of an arcuate slot rather than circular, the plate 66, having served its function of unclutching said shafts, may now swing back into its normal position shown in Fig. 2. If desired, a spring may be provided to actuate the plate in its return movement, but no such means are essential inasmuch as said plate will be carried back to its normal position when the shafts are

again clutched together upon the tripping of the finger 48 by the slide 49.

A horizontal aperture 74 is formed in the slide 71, and receives a loosely fitting rod 75, one end of which extends beyond the surface of the slide into the path of the lug 59 on the gear wheel 57. The other end passes through an opening in the end wall of the machine casing and is there pivoted to an upright rigid extension 76^a on a holding arm 76. This arm is pivoted at 77 to an exterior 75 base portion of the casing 10. A notch 78 for receiving a loop or bend in one end of the wire to be tied is cut in one end of the arm 76, while the other end of the arm is normally drawn toward the end wall of the casing by a spring 79. As long as the wire 14 is tensioned but uncut, the end of the arm 76 to which the wire is attached will be drawn in toward the casing, and the rod 75, being pivoted to the upright extension of the arm 76 on the far side of its pivoting point 77, will be shifted outwardly so as to be withdrawn out of the path of the lug 59 on the gear wheel 57. The purpose in withdrawing the rod 75 temporarily from its operative position will be set forth later.

The cutting mechanism will now be described. Referring particularly to Figs. 3, 8 and 9, it will be seen that the previously mentioned shaft 58 on which the gear wheel 57 is keyed, is provided at both of its ends with similar cams 80 and 81. The cam 80 is attached to its shaft exteriorly of the casing, while the cam 81 is attached to its shaft within the casing adjacent the partition 18. 100 A cam-operated cutting arm 82 is pivoted to the casing against a wire positioning slot 83, and, just before the twisting of the wire is completed and the shafts 39 and 15 unclutched by the mechanism previously described, the cam 80 forces the arm 82 to sever the inner wire in the slot 83. The wire thus cut away represents the excess portion of that end of the wire remaining after the twisting operation.

110 A somewhat similar cam-operated cutting arm 84 is pivoted in alignment with the cam 81 against a corresponding wire positioning slot 85. The cutting arm 84 however serves to sever the outer wire in the slot 85. The wire thus cut away represents the excess portion of the other end of the wire remaining after the twisting operation. Leaf springs 86 are attached to the casing and bear against the cutting arms 82 and 84 in order 115 to return said arms to their raised positions upon the completion of the cutting operations.

Because of the force required to operate these cutting arms, the cams are so keyed to the shaft 58 that the cutting arm 84 functions a very short time before the cutting arm 82, thus dispensing with the necessity

of exerting a force sufficient to make both cuttings simultaneous.

The operations of the cutting arms occur slightly before the twisting mechanism has completed its work. The reason for this is to permit the wire-holding arm 76 to spring back upon the release of the tension and thereby insert the rod 75 into the path of the approaching lug 59 on the gear wheel 57, 10 and, at the other end, to permit the spring 25 to re-engage the clutch teeth 21 and 23 and return slide 49 to its original position so that its tapered notch 51 will be free of finger 48, thus allowing plunger 46 to engage notch 45 of shaft 39 upon the operation of the unclutching mechanism.

The twisting pinion 60 is meshed with the gear wheel 57 in such relation that the wire will be twisted a portion of a turn past the 20 horizontal position of the slot 63 in the pinion. This is done in order to leave the wire in horizontal alignment and permit its full withdrawal from the slot, after the natural reflex of the twisted and tensioned wire 25 has occurred. This action of the wire immediately serves to return the slot 63 of the pinion into a horizontal plane.

To assist this return or backward movement of the pinion 60, the lug 59 on the gear 30 wheel 57, is likewise moved backwards by pressure of spring 72 operating slide 71 carrying rod 75 against lug 59.

If no precautions were taken to remove the end of the rod 75 from the path of this 35 lug, it will be readily seen that, as soon as the twisting operation is set in motion on the next wire to be tied, the twisting mechanism would be immediately unclutched and brought to rest. In order to obviate this 40 difficulty, the withdrawal of the end of the rod 75 is brought about in the manner previously described by the tensioning of the wire attached to arm 76.

In use, the machine is placed upon the box to be wired, with the wire engaging side of the machine in substantially the same plane as the desired band of wire. A wire of the correct length with a loop or bend formed in one end thereof, is hooked over the notch 50 of the wire-holding arm 76. The wire is then inserted in the slot of the twisting pinion and in the other positioning slots aligned therewith, passed around the box, again inserted in said slots, and the remaining other end portion engaged in one of the kerfs of the drum 37. The wire is thus properly attached to the machine, and is ready to be tensioned, twisted, and cut.

The hand-wheel 33 is now turned in a 55 clockwise direction, causing the drum 37 to rotate in a counter-clockwise direction, whereby the wire is gradually drawn taut and tensioned. As the slack is taken out of the wire the end of the wire-holding arm 76 is drawn inwardly and moves the end of

rod 75 out of the path of the lug 59 on the gear wheel 57. As soon as the wire has become properly tensioned, the drum 37 comes to rest and the spring 25 yields. As the spring 25 yields, the slide 49 is shifted by 70 the disk 24 and the nose of plunger 46 is withdrawn from the groove in the shaft 39, causing said shaft, under the pressure of the spring 44 to clutch with shaft 15 and be driven thereby. The clutching in of the 75 shaft 39 commences the twisting of the wire ends. Just prior to the completion of the twist the cutting arms are actuated by their cams and the wire ends are cut. The cutting of the excess wire at 85 by the cutting 80 arm 84 releases the tension on the drum 37 and allows the spring 25 to return the worm 22 to its original position in clutched engagement with the shaft 15. The slide 49 with its tapered slot 51 is thereby shifted to its original position and allows plunger 46 to bear against the surface of shaft 39 in order subsequently to engage slot 45 when unclutching mechanism operates. As soon as the wire end is cut at slot 83 by cam operated arm 82, the tension is removed from the notched end of the wire-holding arm 76, and rod 75 is shifted into the path of the lug 59. Upon coming into contact with the end of the rod 75, the lug moves the end of 95 said rod laterally, and the slide 71 is shifted in its guideway accordingly. As a result of this movement of the slide 71, plate 66 is swung about its pivot, and the shaft 39 shifted into an unclutched position. In 100 this unclutching operation the spring 72 is compressed. After unclutching it operates to bring the slide 71 carrying the rod 75 against the lug 59 to rotate the gear 57 and the twisting pinion 60 with its slot 63 back 105 to a horizontal position, thereby allowing the wire to be removed easily from the twisting slot 63. The twisting mechanism is now completely disengaged until again set in motion by the tensioning of another wire 110 band.

The machine may now be withdrawn, leaving the wire neatly and efficiently tied and the box securely bound.

The embodiment of the invention here disclosed is adapted obviously for hand operation, but such a device may be motor driven, if desired, by merely attaching to the cover thereof, or to some convenient portion of the casing, an electric motor properly geared to 115 the drive shaft of the machine.

I claim:

1. In a machine of the character described, the combination with means for holding one end of a wire, of means for tensioning the 120 wire a predetermined amount, including a driven shaft, rotatable means normally in clutched engagement with said shaft and having attached thereto the other end of the wire, and means to unclutch the last men- 125

tioned means from said driven shaft when the tension of the wire reaches the predetermined amount.

2. In a machine of the character described, the combination with means for holding one end of a wire, of means for tensioning the wire automatically a predetermined amount including a driven shaft, rotatable means normally in clutched engagement with said 10 shaft and having attached thereto the other end of the wire, and means to unclutch the last mentioned means from said driven shaft when the tension of the wire reaches the predetermined amount, and means for adjusting said tensioning means whereby to determine the amount of tension given the wire.

3. In a machine of the character described, the combination with means for holding one end of a wire, of means for tensioning the 20 wire automatically a predetermined amount including a driven shaft, a worm longitudinally movable thereon and clutched thereto when at one end only of its movement, yieldable means for normally maintaining said worm at that end of its movement in which it is clutched to the shaft, a worm gear in mesh with said worm, and means driven by said worm gear for holding the 25 other end of the wire and effective under 30 resistance from the tensioned wire to induce movement of the worm longitudinally of the shaft against the yieldable means.

4. In a machine of the character described, the combination with means for 35 holding one end of a wire, of means for tensioning the wire automatically a predetermined amount including a driven shaft, a worm longitudinally movable thereon and clutched thereto when at one end only of 40 its movement, yieldable means for normally maintaining said worm at the end of its movement in which it is clutched to the shaft, a worm gear in mesh with said worm, means driven by said worm gear for holding 45 the other end of the wire and effective under resistance from the tensioned wire to induce movement of the worm longitudinally of the shaft against the yieldable means, and means for adjusting said tensioning means whereby to determine the 50 amount of tension given the wire.

5. In a machine of the character described, the combination with means for holding one end of a wire, of means for tensioning the wire automatically a predetermined amount including a driven shaft, a worm longitudinally movable thereon and clutched thereto when at one end only of its 55 movement, yieldable means for normally maintaining said worm at the end of its movement in which it is clutched to the shaft, a worm gear in mesh with said worm, means driven by said worm gear for holding the other end of the wire and effective under resistance from the tensioned wire 60

to induce movement of the worm longitudinally of the shaft against the yieldable means, and means for adjusting said tensioning means whereby to determine the amount of tension given the wire, said means comprising a screw plug bearing member adapted to vary the resistance offered to the longitudinal movement of the worm by the yieldable means. 70

6. In a machine of the character described, the combination with means for holding one end of a wire, of means for tensioning the wire automatically a predetermined amount including a driven shaft, a worm longitudinally movable thereon and clutched thereto when at one end only of its movement, yieldable means for normally maintaining said worm at that end of its movement in which it is clutched to the shaft, a worm gear in mesh with said worm, 80 means rotated by said worm gear for holding the other end of the wire and effective under resistance from the tensioned wire to induce movement of the worm longitudinally of the shaft against the yieldable means, and means for intertwisting overlapped portions of the wire adjacent the ends thereof. 85

7. In a machine of the character described, the combination with means for holding one 90 end of a wire, of means for tensioning the wire automatically a predetermined amount including a driven shaft, a worm longitudinally movable thereon and clutched thereto when at one end only of its movement, yieldable means for normally maintaining said worm at that end of its movement in which it is clutched to the shaft, a worm gear in mesh with said worm, means rotated by said worm gear for holding the other end of the wire and effective under resistance from the tensioned wire to induce movement of the worm longitudinally of the shaft against the yieldable means, means for adjusting said tensioning means whereby to determine the amount of tension given the wire, and means for intertwisting overlapped portions of the wire adjacent the ends thereof. 100

8. In a machine of the character described, the combination with means for holding the 110 ends of a wire, of means for tensioning the wire automatically a predetermined amount, means for intertwisting overlapped portions of the wire adjacent the ends thereof, and means for automatically putting into operation the twisting means when the wire has acquired a predetermined amount of tension. 115

9. In a machine of the character described, means for intertwisting overlapped portions 120 of a wire adjacent the ends thereof including a driven shaft, a second shaft co-axial and clutched with said first shaft, a gear wheel, means for rotating said gear wheel by said second shaft, and means rotating with said 125 second shaft, and means rotating with said 130

gear wheel and slotted to receive therein said overlapped portions of the wire in order to twist the same.

10. In a machine of the character described, the combination with means for holding the ends of a wire, of means for tensioning the wire automatically a predetermined amount, means for intertwisting overlapped portions of a wire adjacent the ends thereof including a driven shaft, a second shaft co-axial and clutchable with said first shaft, a gear wheel, means for rotating said gear wheel by said second shaft, and means driven by said gear wheel and slotted to receive therein said overlapped portions of the wire in order to twist the same.

11. In a machine of the character described, means for intertwisting overlapped portions of a wire adjacent the end thereof including a driven shaft, a second shaft co-axial and clutchable with said first shaft, a gear wheel, means for rotating said gear wheel by said second shaft, a pinion meshed with said gear wheel and slotted to receive therein said overlapped portions of the wire in order to twist the same, and means for automatically putting into operation the twisting means when the wire has acquired the predetermined tension.

12. In a machine of the character described, the combination with means for holding the ends of a wire, of means for tensioning the wire automatically a predetermined amount, means for adjusting said tensioning means whereby to determine the amount of tension given the wire, means for intertwisting overlapped portions of a wire adjacent the end thereof, including a driven shaft, a second shaft co-axial and clutchable with said first shaft, a gear wheel, means for rotating said gear wheel by said second shaft, and a pinion meshed with said gear wheel and slotted to receive therein said overlapped portions of the wire in order to twist the same.

13. In a machine of the character described, the combination with means for holding the ends of a wire, of means for tensioning the wire automatically a predetermined amount, means for adjusting said tensioning means whereby to determine the amount of tension given the wire, means for intertwisting overlapped portions of a wire adjacent the end thereof, including a driven shaft, a second shaft co-axial and clutchable with said first shaft, a gear wheel, means for rotating said gear wheel by said second shaft, a pinion meshed with said gear wheel and slotted to receive therein said overlapped portions of the wire in order to twist the same, and means for automatically putting into operation the twisting means when the wire has acquired the predetermined tension.

14. In a machine of the character de-

scribed, the combination with means for holding one end of a wire, of means for tensioning the wire automatically a predetermined amount including a driven shaft, a worm longitudinally movable thereon and clutched thereto when at one end only of its movement, yieldable means for normally maintaining said worm at that end of its movement in which it is clutched to the shaft, a worm gear in mesh with said worm, said means rotated by said worm gear for holding the other end of the wire and effective under resistance from the tensioned wire to induce movement of the worm longitudinally of the shaft against the yieldable means, means for intertwisting overlapped portions of the wire adjacent the ends thereof including a driven shaft, a second shaft co-axial and clutchable with said driven shaft, a gear wheel, means for rotating said gear wheel by said second shaft, and a pinion meshed with said gear wheel and slotted to receive therein said overlapped portions of the wire in order to twist the same.

15. In a machine of the character described, the combination with means for holding one end of a wire, of means for tensioning the wire automatically a predetermined amount including a driven shaft, a worm longitudinally movable thereon and clutched thereto when at one end only of its movement, yieldable means for normally maintaining said worm at that end of its movement in which it is clutched to the shaft, a worm gear in mesh with said worm, and means rotated by said worm gear for holding the other end of the wire and effective under resistance from the tensioned wire to induce movement of the worm longitudinally of the shaft against the yieldable means, means for intertwisting overlapped portions of the wire adjacent the ends thereof including a driven shaft, a second shaft co-axial and clutchable with said driven shaft, a gear wheel, means for rotating said gear wheel by said second shaft, a pinion meshed with said gear wheel and slotted to receive therein said overlapped portions of the wire in order to twist the same, and means for automatically putting into operation the twisting means when the wire has acquired the predetermined tension.

16. In a machine of the character described, the combination with means for holding one end of a wire, of means for tensioning the wire automatically a predetermined amount including a driven shaft, a worm longitudinally movable thereon and clutched thereto when at one end only of its movement, yieldable means for normally maintaining said worm at that end of its movement in which it is clutched to the shaft, a worm gear in mesh with said worm, and means rotated by said worm gear for

holding the other end of the wire and effective under resistance from the tensioned wire to induce movement of the worm longitudinally of the shaft against the yieldable means, means for intertwisting overlapped portions of a wire adjacent the ends thereto including a driven shaft, a second shaft co-axial and clutchable with said driven shaft, a gear wheel, means for rotating said gear wheel by said second shaft, a pinion meshed with said gear wheel and slotted to receive therein said overlapped portions of the wire in order to twist the same, means for automatically setting into operation the twisting means when the wire has acquired the predetermined tension, said last mentioned means including means tending to clutch the second shaft with the driven shaft, means acting to prevent said clutching, and means actuated when the wire has acquired the predetermined amount of tension to make inoperative the last mentioned means.

17. In a machine of the character described, the combination with means for holding one end of a wire, of means for tensioning the wire automatically a predetermined amount including a driven shaft, a worm longitudinally movable thereon and clutched thereto when at one end only of its movement, yieldable means for normally maintaining said worm at that end of its movement in which it is clutched to the shaft, a worm gear in mesh with said worm, and means rotated by said worm gear for holding the other end of the wire whereby when a predetermined amount of tension is placed upon the wire said tension will exert tangentially of the gear a force on the worm to move the same longitudinally of the shaft against the yieldable means, means for intertwisting overlapped portions of the wire adjacent the ends thereof including a driven shaft, a second shaft co-axial and clutchable with said driven shaft, a gear wheel, means for rotating said gear wheel by said second shaft, a pinion meshed with said gear wheel and slotted to receive therein said overlapped portions of the wire in order to twist the same, means for automatically putting into operation the twisting means when the wire has acquired the predetermined tension, said last mentioned means including a disk mounted loosely on the driven shaft and moved longitudinally thereof by the worm, a spring tending to clutch the second shaft with the driven shaft, a plunger acting against said second shaft to prevent said clutching, and a slide engaging said disk acting to withdraw the plunger from operative position when shifted by the disk upon longitudinal movement of the worm.

18. In a machine of the character described, the combination with means for holding the ends of a wire, of means for

tensioning the wire automatically a predetermined amount, means for intertwisting the overlapping portions of the wire adjacent the ends thereof, means for automatically setting into operation the twisting means when the wire has acquired the predetermined amount of tension, and means for automatically putting out of operation the twisting means when the wire has been sufficiently twisted. 75

19. In a machine of the character described, the combination with means for holding the ends of a wire, of means for tensioning the wire automatically a predetermined amount, means for intertwisting the overlapping portions of the wire adjacent the ends thereof, means for automatically setting into operation the twisting means when the wire has acquired the predetermined amount of tension, means for automatically putting out of operation the twisting means when the wire has been sufficiently twisted, and means associated with the wire-holding means for rendering said last mentioned automatic means inoperative as long as said wire-holding means holds both ends of the wire under tension. 80

20. In a machine of the character described, the combination with means for holding the ends of a wire, of means for tensioning the wire automatically a predetermined amount, means for adjusting said tensioning means whereby to determine the amount of tension given the wire, means for intertwisting overlapping portions of the wire adjacent the ends thereof, means for automatically setting into operation the twisting means when the wire has acquired the predetermined amount of tension, and means for automatically putting out of operation the twisting means when the wire has been sufficiently twisted. 95 100

21. In a machine of the character described, the combination with means for holding the ends of a wire, of means for tensioning the wire automatically a predetermined amount, means for intertwisting overlapping portions of the wire adjacent the ends thereof, separate means for cutting off each end of the wire at points closely adjacent the ends of the twisted portion, said separate means consecutively operating to cut off the wire ends. 110 115

22. In a machine of the character described, the combination with means for holding the ends of a wire, of means for tensioning the wire automatically a predetermined amount, and means for intertwisting overlapped portions of the wire adjacent the ends thereof, said last mentioned means serving to twist said overlapped portions of the wire beyond the position at which they would come to rest after the removal of the twisting force and the reflex of the wire. 120 125

23. In a machine of the character described, the combination with means for holding the ends of a wire, of means for tensioning the wire automatically a predetermined amount, means for intertwisting overlapped portions of the wire adjacent the ends thereof, and means for turning the twisting means backward after said twisting means has become carried past the required number of twists and has been un-clutched.

In testimony whereof I have hereunto subscribed my name in the presence of two subscribing witnesses.

WILLIAM G. MUELLER.
